UNITED STATES PATENT OFFICE.

LUTHER L. KNOX, OF AVALON, PENNSYLVANIA, ASSIGNOR TO BIAW-KNOX COMPANY, OF PITTSBURGH, PENNSYLVANIA, A CORPORATION OF NEW JERSEY.

VALVE SYSTEM FOR REVERSING-FURNACES.

1,351,914.

Specification of Letters Patent. Patented Sept. 7, 1920.

Application filed December 21, 1916. Serial No. 138,288.

To all whom it may concern:

Be it known that I, LUTHER L. KNOX, a citizen of the United States, residing at Avalon, Allegheny county, Pennsylvania, have invented a new and useful Valve System for Reversing-Furnaces, of which the following is a full, clear, and exact description, reference being had to the accompanying drawings, forming part of this specification, in which—

Figure 1 is a plan view showing a valve system for reversing furnaces embodying my invention, and

Figs. 2 and 3 are sections taken on the lines II—II and III—III, respectively, of Fig. 1.

My invention has relation to valve systems for reversing regenerative furnaces and is designed to provide operating mechanism for the several gas and air valves which is positive in its action and simple and effective in its construction and arrangement. A further object is to provide mechanism of this character in which certain of the valves may be operated in a definite time relation to each other.

The nature of my invention will be best understood by reference to the accompanying drawings in which I have shown the preferred embodiment thereof, and which will now be described, it being premised, however, that various changes can be made in the details of construction and arrangement of the several parts without departing from the spirit and scope of my invention as defined in the appended claims.

In these drawings the numeral 2 designates an air flue leading from one side of the valve structure to one of the air regenerators (not shown) of a reversing regenerative furnace; and 2^a a similar flue leading from the other side of the valve structure to the other air regenerator. 3 and 3^a designate the gas flues leading from opposite sides of the valve structure to the respective gas regenerators. The air flue 2 is provided with an air inlet valve 4 and an air reversing valve 5, and the flue 2^a is provided with corresponding valves 4^a and 5^a. The gas flue 3 has the respective branches 6 and 7, the branch 6 having therein the gas reversing valve 8, and the branch 7 having therein the gas inlet valve 9. The flue 3^a

has similar branches 6^a and 7^a, provided with gas reversing and inlet valves 8^a and 9^a, respectively. 10 designates a gas inlet leading to one end of the valve structure and which communicates with both flue branches 7 and 7^a. The branches 6 and 6^a have a common connection 11 between the valves 8 and 8^a leading to the stack connection 12 extending from the opposite end of the valve structure. The two air flues 2 and 2^a also connect with the flue 12 between the valves 5 and 5^a. 13 designates a stack damper in the stack connection 12. The valves 5 and 5^a, 8 and 8^a, and 9 and 9^a are preferably of the vertically sliding type, such as illustrated in Figs. 2 and 3, and may consist of hollow water cooled bodies. I also prefer to seat these valves obliquely across their respective flues.

The air inlet valves 4 and 4^a are preferably of the mushroom type, such, for instance, as shown in Fig. 2. The details of the particular valves themselves form no part of my present invention.

14 designates an electric motor which is connected through suitable gearing 15 with a shaft 16. This shaft 16 carries one double pulley 17, a second double pulley 18, and a third double pulley 19. 20 is a cable which is connected at one end to one member of the double pulley 17 and which extends thence over a guide pulley 21 and down to a yoke 22 which has a sliding lost motion engagement with the headed stem 23 of the air inlet valve 4. The pulley 21 is preferably mounted on the pivoted arm 21¹ having a control connection 21² leading to any suitable form of manual control device. This connection 21² provides means whereby, by raising or lowering the arm 21¹, the opening movement of the valve 4 may be regulated, and also whereby said valve may be, if desired, operated manually independently of its connections with the motor 14. 20^a is a similar cable leading from the other member of the double pulley 17 and connected to the valve 4^a in the same manner that the cable 20 is connected to the valve 4.

24 is a cable which is connected at one end to one end of the double pulley 18, passing thence over the guide pulley 25 and connected at its opposite end to the air reversing valve 5. A similar cable 24^a is con-

nected to the other member of the double pulley 18 and passes thence over the guide pulley 25^a to the air reversing valve 5^a.

26 is a cable connected at one end to one member of the double pulley 19 and at its opposite end to the gas reversing valve 8.

26^a is a similar cord or cable connected at one end to one member of the double pulley 19 and at its opposite end to the gas reversing valve 8^a. 27 and 27^a are guide pulleys for the cables 26 and 26^a, respectively.

28 designates another electric motor which is connected by suitable gearing 29 with a double pulley 30. 31 is a cable connected 15 to one member of the double pulley 30, passing thence over guide pulleys 32 and connected at its other end to the gas inlet control valve 9. 31^a is a similar cable connected at one end to the other member of the double pulley 30, passing over the guide pulleys 32^a, and connected at its other end to the gas inlet control valve 9^a. 33 is a counterweight which is hung on the cable 31 between the pulleys 30 and 32, and 33^a is a similar counterweight hung on the cable 31^a.

The operation is as follows: Supposing the several valves to be in the positions shown in Figs. 2 and 3, in which air and gas are passing to the furnace through the flues 2^a and 3^a and the products of combustion are returning through the flues 2 and 3 and passing to the stack connection, and that it is desired to reverse the furnace:—The motors 14 and 28 are energized, thereby 30 actuating the several valve connections described to close the valves 5, 4^a; 8 and 9^a, and to open the valves 5^a, 8^a and 9. The air inlet valve 4 will also open as soon as the lost motion connection between the yoke 40 22 and the headed valve stem 23 is taken up by the movement of the cable 20.

By reference to Fig. 3 it will be noted that with the parts in the position which they occupy prior to the reversal just described, 45 the cable 31 has considerable slack between the pulleys 30 and 32, and that the counterweight 33 is in its lowermost position, this counterweight being lighter than the weight of the valve 9. The other counterweight 50 33^a, however, is in its raised position and the cable 31^a is taut. Therefore, when the pulley 30 is operated the cable 31^a is immediately slackened and the valve 9^a at once commences to close. Before any operation of 55 the valve 9 it is first necessary for the pulley 30 to turn sufficiently to take up the slack in the cable 31 and raise the counterweight. There will, therefore, be a certain time interval between the operation of the 60 two valves 9^a and 9, the valve 9^a being substantially closed before the valve 9 begins to open. In this manner no gas is admitted to the flue 3 until the other valves of the system have been closed, while at the same time 65 the gas which has been passing to the flue 3^a

is immediately closed off when the valves start to reverse. There results a minimum loss of gas during the reversing period, due to its being carried into the stack without passing into the furnace.

The advantages of my invention result 70 from the provision of simple and positive means for mechanically operating the several valves through the medium of motors which may be controlled in any desired 75 manner. Also from the provision of means just described whereby a time interval elapses between the closing of one gas inlet control valve and the opening of the other gas inlet control valve. By the described 80 arrangement, all the valves may be operated by simple connections from two motors.

It will be readily understood that the particular connections between the valves and the motors may be changed in various ways; 85 the details of construction of the valves themselves may be changed, and that numerous other changes may be made within the scope of the appended claims.

I claim:

1. In a valve system of the character described, the combination with air and gas flues leading to opposite ends of the furnace, each of the air flues having an air inlet valve and also an air reversing valve, each 95 of the gas flues having a gas reversing valve, a gas inlet, each of the gas flues having a gas inlet valve, a shaft having actuating devices thereon for all of the air inlet valves, air reversing valves and gas reversing 100 valves, a second actuating device for the gas inlet valves, lost motion devices between the air inlet valves and their actuating mechanism, and lost motion devices between the gas inlet valves and their actuating 105 devices, said shaft and actuating devices being arranged to permit the operation of the several recited valves in a predetermined sequence, substantially as described.

2. In a valve system of the character de- 110 scribed, the combination with air and gas flues, leading to opposite ends of a furnace, each of the air flues having an air inlet valve and also an air reversing valve, each of the gas flues having a gas reversing valve, an 115 actuating device for all of said valves, lost motion connections between said actuating devices and the air inlet valves, arranged to cause the air inlet valves and the reversing valves to be operated in a predetermined 120 sequence, gas inlet valves for the gas flues, and a separate operating device for actuating the gas inlet valves, there being sufficient lost motion in said actuating devices to permit the actuation of all of the other valves 125 after the one gas inlet valve has been closed and before the other gas inlet valve has been opened, substantially as described.

3. In a valve system of the character de- 130 scribed, the combination with air and gas

flues leading to opposite ends of the furnace, each of the air flues having an air inlet valve and an air reversing valve, and each of the gas flues having a gas inlet control valve and a gas reversing valve, a motive device, a shaft driven thereby, cables leading in opposite directions from said shaft and connected to the respective air inlet valves, an adjustable lost motion connection between each of the air inlet valves and their cable connections to permit the one valve to close before the other is opened when reversing the furnace, a second set of cables leading from said shaft and connected 15 respectively to the two air reversing valves, a third set of cables connected to said shaft and leading in opposite directions to the gas reversing valves, a second motive device, and connections operated thereby and connected to the gas inlet control valves, the cables 20 leading to the gas inlet control valves also having means for producing lost motion therein, said motive devices and connections being arranged to permit operation of the several valves in predetermined sequence, 25 substantially as described.

In testimony whereof, I have hereunto set my hand.

LUTHER L. KNOX.
